United States Patent Office

Des. 182,899
Patented May 27, 1958

182,899

PILLOW COVER OR SIMILAR ARTICLE

Jadwiga Jablonska, Swampscott, Mass.

Application June 21, 1957, Serial No. 46,685

Term of patent 3½ years

(Cl. D3—9)

The figure is a front view of a pillow cover showing my new design.

The rear of the pillow cover is substantially the same in appearance as the front.

I claim:

The ornamental design for a pillow cover or similar article, substantially as shown, and described.
